UNITED STATES PATENT OFFICE

172,917

TRAY FOR FRANKFURTERS OR SIMILAR ARTICLE

Ray Bang, Brainerd, Minn.

Application February 16, 1954, Serial No. 29,044

Term of patent 14 years

(Cl. D58—26)

To all whom it may concern:

Be it known that I, Ray Bang, a citizen of the United States, residing at Brainerd, in the county of Crow Wing and State of Minnesota, have invented a new, original, and ornamental Design for a Tray for Frankfurters or Similar Article, of which the following is a specification, reference being had to the accompanying drawing, forming part thereof.

Figure 1 is a perspective view of a tray for frankfurters or similar article, showing my new design;

Figure 2 is a developed top plan view on a reduced scale of the blank from which the tray for frankfurters or similar article is made; and

Figure 3 is a developed bottom plan view on a reduced scale of the blank.

The dominant feature of my design resides in the portions shown in full lines.

I claim:

The ornamental design for a tray for frankfurters or similar article, as shown and described.
